UNITED STATES PATENT OFFICE.

FRED B. HAYES, OF FORT WAYNE, INDIANA, ASSIGNOR TO WESTERN GAS CONSTRUCTION COMPANY, OF FORT WAYNE, INDIANA, A CORPORATION OF INDIANA.

PROCESS OF MAKING CARBURETED WATER GAS.

Application filed September 25, 1924. Serial No. 739,757.

This invention relates to process of making carbureted water gas.

The conventional apparatus for making carbureted water gas, including a water gas generator, carbureter, superheater, air blower and various apparatus valves, tar batter or seal, and connections, operates upon what is known as the "up run and down run system"; that is to say, after the air blast has 10 carried the products of combustion of the heating medium from the generator into and through the carbureter and the superheater, and after the checker brick therein have been heated to a desired, predetermined temperature, steam is passed into the generator for 15 the gas making period, first at the bottom of the generator for the "up run" and then at the top of the generator for the "down run", and, usually, again at the bottom of 20 the generator for a very brief period or second "up run", after which the blast is resumed and the cycle of operations repeated.

It has been found in practice that during the down run period and again during the 25 brief second up run period, the temperature in both the carbureter and superheater becomes materially lowered, with the result that it becomes necessary to very frequently "over blast" the generator in order to restore the proper temperatures. This over blasting is accomplished, of course, at the expense of extra power and fuel.

It is required to measure the volume or 30 quantity of oil to be gasified in each cycle of operations, in proportion to the quantity of blue water gas produced in the generator during each run period. When the oil is admitted during the up run period only, it must be flowed at a relatively high speed, 35 and this produces certain disadvantages and not the best results. When this volume of oil is flowed at a lower speed, so as to enter the carbureter during both the up run and down run periods, it is found that the oil 40 does not properly gasify during the down run on account of the lowered temperature in the carbureter, produced by the lower 45 temperatures of the down run gases.

Improper gasification of the oil produces 50 carbon impurities which not only become attached to the checker brick and render the same inefficient for proper functioning, but which also form as a layer or carbon deposit on the top of the checker brick and clog up 55 the carbureter. It thus becomes necessary

from time to time to shut down the apparatus to remove this carbon deposit and clear the checker brick, and frequently replace the latter with new brick.

The principal object of the present invention is to obviate or reduce to a negligible factor all of these objections, and to maintain more uniformly and constantly a desired temperature in the carbureter and 60 superheater.

Another object of the invention is to effect a proper gasification of the oil by flowing into the carbureter the desired quantity for each gas making period, part during the up run and part during the down run, thus 70 avoiding a rate of flow which produces flooding and improper gasification, and whereby a heavier and cheaper grade of oil may be used than is possible with present 75 apparatus.

To this end, my invention consists in the process of making gas, wherein gaseous products formed in the generator are, during the down run period, passed from the generator either to the superheater or to the tar batter seal or other receptacle, without at all passing through the carbureter; in gasifying a part of the oil for each gas making period during the down run period; and in enriching the gases produced on the down run by commingling said down run gases with the carbureted up run gases outside of and beyond the carbureter.

My improvement in the process of making carbureted water gas may be practiced by 80 various apparatus, several forms of which I have herein illustrated. In that form of conventional apparatus now extensively in use, wherein the conduits from the generator to the carburetor are governed by hot valves or reversing valves, of either the one unit or two unit type, the lower conduit or 85 down run pipe is disconnected from the top of the carbureter and said conduit or pipe is led into the superheater, either at the top or at the bottom; or into the bottom or lowest passageway of the carbureter from whence the products of the down run would 90 pass directly into the bottom of the superheater without passing through the carbureter.

An alternative apparatus would eliminate reversing valves between the generator and carbureter, and require the disconnection 95 from the carbureter of the conduit from the 100

bottom of the generator for the down run, and leading said conduit from the bottom of the generator directly into the tar batter, seal or other container. In this latter case, 5 however, reversing valves should be located, preferably in the tar batter, to govern both the conduit leading from the top of the superheater and the conduit for the down run leading from the generator to the tar 10 batter, so that either one or the other may be closed as required in reversing from the up run to the down run, or from the down run to the up run cycle of operations.

These various arrangements will be fully 15 understood by those skilled in the art, by reference to the accompanying illustrative drawings of the main features of said apparatus, and in which I have not attempted to illustrate all of the details of such apparatus, 20 as such details are well known and in common use in water gas jets.

In said drawings, Fig. 1 is an illustrative view, partially in vertical section, of the main elements of a conventional form of 25 water gas set by which my process may be carried out.

Fig. 2 is an elevation showing a modified form of apparatus for the same purpose.

Fig. 3 is a plan view of a modified form 30 of the apparatus illustrated in Fig. 2.

Fig. 4 and Fig. 5 are views in elevation, similar to Figure 2, showing two other modified forms of apparatus by which the invention may be practiced.

35. In that form of apparatus for carrying out my process, shown in Fig. 1, the water gas generator is indicated at A, the carbureter by B, the superheater by C and the tar batter by D. Steam inlets 1 and 2, governed by 40 suitable valves, not shown, admit steam to the generator below and above the fuel, for the up run and the down run respectively, during the gas making period. 3 is an open conduit between the top of the generator and 45 the top of the carbureter. The oil is sprayed into the carbureter by the usual oil valve 4 and the air blast supplied to the generator in the usual manner, as by a conduit 5. The exit of gas from the superheater to the tar 50 batter is through the conduit 6, the end 7 of said conduit, in the tar batter, being adapted to be closed by a valve 8.

The blue water gas formed in the generator by the down run steam is conveyed by a 55 conduit E around the carbureter and superheater, directly into the tar batter; the lower end 9 of this conduit in the tar batter being adapted to be closed by the valve 10. The gas exit from the tar batter to a holder (not 60 shown) is indicated at 11.

Within the tar batter D, the valves 8 and 10 may be reversed in any suitable manner. As shown in Fig. 1 they are operatively connected to a rocking lever 12 which is operated and controlled by a hydraulic motor 13.

14 is the usual conduit between the lower part of the carbureter and the bottom of the superheater.

This apparatus will operate as follows: The various valves being properly set for the 70 air blast period, the latter will be continued until the checker brick in the carbureter and superheater reach the desired temperatures, say 1650° and 1400° F., respectively, when the air blast valve is closed. Then the steam 75 up run of the gas making period is started and water gas is carried from the generator through the conduit 3 into the top of and down through the carbureter, through the passage 14, into and up through the super- 80 heater, and through the conduit 6 into the tar batter D. During this up run the valve 8 is open and the valve 10 closed. The oil is flowed at a proper rate into the top of the carbureter where oil gas is formed in the 85 usual manner and this will pass with the water gas from the carbureter into and up through the superheater, in the usual way.

During the steam down run, the valves 8 and 10 are reversed, the end of the conduit 90 6 being closed and the end of the conduit E being open. This permits the gases formed in the generator by the down run steam to pass from the generator through the conduit E directly to the tar batter D. 95

In the down run, in that form of apparatus wherein hot valves are used between the generator and carbureter, said valves are closed, so that blue water gas made in the generator by down run steam by-passes the 100 carbureter in going to the seal box D. Simultaneously with the making of blue water gas in the water gas generator by down run steam, oil gas is made in the carbureter without being in contact with the water gas. Ultimately the down run blue water gas and the oil gas are commingled in the seal box 105 D from whence they pass through exit 11 to a holder.

In that form of apparatus illustrated in 110 Figs. 2 and 3, the conduit E leads from the generator A and enters the top of the superheater C at 15, instead of into the tar batter D (as shown in Fig. 1). The tar batter is not provided with reversing valves and may 115 be of any conventional construction. In this form of apparatus, reversing or "hot valves" 16 and 17 will be located adjacent the generator, in conduits 3 and E. These valves may be hand operated, of the single 120 or double unit type, but, preferably, will be mechanically and automatically operated by any of the well known devices available for this purpose. The oil will be flowed into the top of the carbureter B at a lower rate of 125 speed, so that a portion of the required quantity of oil for a gas making period will flow into the carbureter during the steam up run and the balance during the steam down run. 18 is a valve controlled steam inlet 130.

in the top of the carbureter B through which steam is admitted to react with the oil to form oil gas in the carbureter during the down run period, and to force such oil gas through the carbureter toward the superheater.

In the form of apparatus shown in Fig. 4, the valved conduit E leads directly into the bottom of the carbureter B and the gases produced by the down run will not be subjected to the action of the carbureter, but will pass through the passage 14 into the bottom of and upwardly through the superheater C. The reversing valves 16 and 17 and steam jet valve 18, as explained for the apparatus shown in Figs. 2 and 3, will be used.

The apparatus shown in Fig. 5 is the same as that shown in Fig. 4, except that the conduit E leads directly from the generator A around the carbureter, to the superheater, where contact is made at 19.

By passing the gases produced by the down run around and not through the carbureter, I practically eliminate the various objections herein above noted. With existing apparatus and practice, the temperature of the generator becomes lowered by steam during the up run period, and the steam to produce a down run still further lowers it; and the temperature of the blue gas produced by the down run varies from 400° F. to 250° F. as it enters the top of the carbureter. The effect of this, in existing practice, together with the incoming cold oil, still further reduces the temperature in the top of the carbureter to 700° F. or lower, and, accordingly, the temperature of the lower part of the carbureter is also lowered.

In practicing my invention, I do not introduce the down run gases into the carbureter and the temperature therein at the conclusion of an up run is not therefore substantially reduced and remains at a desirably high temperature during the balance of the gas making period. Thus the bad effects of lower temperature of the checker brick and the necessity for "overblasting" the generator to restore the temperature, is avoided.

Another advantage of my process lies in the fact that the entire heat in the carbureter is utilized for gasifying the oil. Heretofore the carbureter has been obliged to superheat the down run blue gas coming from the bottom of the generator. By putting part of the oil into the carbureter at a slower rate of flow, during the steam up run, and part during the period of the steam down run, all the heat in the carbureter is utilized to form oil gas, the carbureter not having been subjected to any substantial temperature reduction by a down run.

The blue water gas from the up run does not absorb any appreciable amount of heat from the carbureter in passing through it,

because it enters the carbureter at high temperatures, since said water gas is formed in the generator immediately after the air blast period when the generator top is hottest. These up run gases, therefore, tend to raise rather than lower the temperature of the carbureter. Thus the heat in the carbureter is conserved for oil gasification, which, ultimately, means that less heat is required in the generator and a decided advantage in fuel economy is effected.

Oil efficiency is also obtained by my process by introducing the oil into the carbureter over a relatively longer period of time, and without flooding. I can make use of a heavier and cheaper grade of oil, than is used in present practice, because of the longer period during which the oil is subjected to cracking and gasification.

Another advantage of my process is that the checker brick are cleaner, do not foul materially because of the slower feed of the oil and better gasification thereof, and therefore repairs and replacement of checker brick are less frequent and the life of the apparatus prolonged.

In my process, the variation between extremes of temperatures in the carbureter is very greatly reduced and the carbureter may be said to be of substantially constant temperature as compared with the temperatures of carbureters in existing apparatus and used in existing practice when the cooler down run gases pass from the generator into and through the carbureter.

Other advantages of my process will be understood by engineers and others familiar with carbureted water gas sets and methods, who will also understand that my process may be carried on by apparatus varying in details from the various forms herein illustratively referred to.

I claim as my invention:

1. The improvement in the process of making carbureted water gas by the alternate up and down steam run method, which consists in passing the up run water gas through a carbureter and simultaneously enriching the same with oil flowed into said carbureter, in by-passing the down run blue water gas with respect to the carbureter, in making oil gas in the carbureter during the steam down run period, and ultimately commingling the by-passed blue water gas, the carbureted water gas and the oil gas in a holder.

2. The improvement in the process of making carbureted water gas by the alternate up and down steam run method, which consists in passing the up run water gas through a carbureter and enriching said gas during the steam up run period only, in by-passing blue water gas of the steam down run outside the carbureter, in forming oil gas in the carbureter during the down run period, and

in ultimately commingling said oil gas and both the carbureted and the uncarbureted water gas in a holder.

3. The improvement in making carbureted water gas by the alternate up and down steam run method, consisting in passing the water gas of the steam up run to a carbureter containing checker brick and enriching the same during the up run period only, 5 in by-passing the blue water gas of the steam down run through a superheater while

avoiding contact with the checker brick in the carbureter, in forming oil gas in the carbureter during the period of the steam down run, and passing said gas through the superheater, and in ultimately commingling said oil gas and both the enriched and the lean water gas of the two runs in a holder. 15

In testimony that I claim the foregoing as my invention, I affix my signature this 20 18th day of September, 1924.

FRED B. HAYES.
